JOHN F. WEBENDORFER, OF NEW YORK, N. Y.

COIN-COUNTER.

1,128,561.

Specification of Letters Patent. Patented Feb. 16, 1915.

Application filed March 18, 1914. Serial No. 825,586.

To all whom it may concern:

Be it known that I, JOHN F. WEBENDORFER, a citizen of the United States, residing at New York, county of New York, State of New York, have invented an Improvement 5 in Coin-Counters, of which the following is a specification.

This invention has for its general objects to provide a machine for automatically 10 counting coins which will be convenient, rapid, and accurate in its operation, which may be readily adjusted to accommodate coins of different sizes or denominations, which will insure the proper counting of 15 every coin passing therethrough, which will be automatically stopped and locked against further operation when a predetermined number of coins has passed, and which may be adjusted within relatively wide limits to 20 provide for the automatic counting of any desired number of coins.

With these and other objects in view I have devised the novel mechanism which I will now describe, reference being had to the 25 accompanying drawings in which:

Figure 1 is a plan view of the complete machine; Fig. 2 is a section on the line 2—2, Fig. 1; Fig. 3 is a section on the line 3—3, Fig. 2; Fig. 4 is a section on the line 4, Fig. 30 1; Fig. 5 is an enlarged plan view of a portion of the mechanism shown in Fig. 1; Fig. 6 is a section substantially on the line 6, Fig. 5, with the coin guide members and certain other parts removed; Fig. 7 is a detail plan 35 view of the adjustable coin guide member; Fig. 8 is a section on the line 8—8, Fig. 7. Fig. 9 is a front elevation of the parts shown in Fig. 5; Fig. 10 is a partial elevation as seen from the right in Fig. 5; Fig. 11 is a 40 section, substantially on the line 11—11, Fig. 9, of the ratchet mechanism; Fig. 12 is a view similar to Fig. 11 showing the use of a second ratchet wheel to increase the counting capacity.

45 15 denotes the main machine frame which may be of any suitable form and size to provide the necessary supports, bearings, and guides for the various machine parts herein-after referred to.

50 16 denotes a stationary tray supported at its forward end by the frame 15 and at its rear end upon legs 114 (see Fig. 1.)

18 denotes a horizontal centrifugal wheel mounted on a vertical shaft 19 journaled in the machine frame 15.

55 44 denotes an upright cylindrical rim formed at the top of the frame 15 and partly surrounding the centrifugal wheel 18, said rim being of such a length as to leave exposed a portion of the edge of the wheel 18, 60 as indicated at 17 in Figs. 1 and 5. The upper edge of the rim 44 extends well above the upper surface of the centrifugal wheel 18 but is on a level with the bottom of the tray 16, the forward edge of which is shaped 65 to fit said rim.

The shaft 19 is provided with a skew gear 20 meshing with a skew gear 201 on a shaft 21 journaled in the machine frame and provided at its ends with a crank 22 by 70 means of which said shaft may be manually rotated, thereby rotating the centrifugal wheel 18.

75 23 (see Figs. 2 and 3) denotes a collar fixed, as by a set screw 24, to the shaft 21 and having one or more notches which are engaged by a spring pressed pawl 25 pivoted to the hub of a worm gear 26 loose on the shaft 21. The worm gear 26 meshes with a worm 27 on a shaft 28 journaled in 80 the machine frame and suitably connected, as by pulleys 29 and 30 and belt 31, with the shaft of a motor 32, preferably an electric motor, suitably supported by the machine frame. The arrangement is such that when 85 the motor 32 is running the movement thereof will be transmitted through the connections above described to the centrifugal wheel 18 in such a manner as to rotate said wheel in a clockwise direction as indicated by arrows 90 in Figs. 1 and 5. At this time the pawl 25, by engagement with the notch or notches in the collar 23, acts to couple the gear 26 to the shaft 21, so that the rotation of said gear is transmitted to the shaft and to the centrifugal wheel. If, however, the shaft 21 be turned in the same direction by the crank 22 the pawl 25 will travel idly on the periphery of the hub 23, so that the shaft 21 95 may be freely turned without causing the movement thereof to be communicated to the gear 26, permitting said gear and the parts connecting the same with the motor 32 to remain at rest.

100

33 (see Figs. 1, 4 and 5) denotes a spring pusher or clearer, secured, as by a screw 34, to the under surface of the centrifugal wheel 18 and having an angular end 35 which projects through an opening 36 in said wheel for a purpose presently to be explained.

37 denotes a horizontally disposed rejecting wheel which is mounted on an upright shaft 38 journaled in a sleeve or bushing 39 which is adjustably held by means of a clamp screw 40 in a split portion 41 of the machine frame. The rejecting wheel 37 is located above the centrifugal wheel 18 and overlaps the exposed portion 17 of the edge thereof, being separated from the upper face of said centrifugal wheel by a space determined by the adjustment of the sleeve or bushing 39, such space in practice being made substantially equal to the thickness of the particular coins to be counted.

42 denotes a worm gear fixed upon the shaft 38 and meshing with a worm 43 on the shaft 21. The worm 43 and skew gear 201 are oppositely disposed or inclined, whereby when the shaft 21 is operated to rotate the centrifugal wheel 18 in a clockwise direction, as indicated by the arrow on Figs. 1 and 5, the wheel 37 will be simultaneously rotated in a counter-clockwise direction, as also indicated by arrows on said figures.

45 denotes a fixed table forming a part of or supported by the machine frame adjacent the exposed portion 17 of the edge of the wheel 18, and with its upper surface substantially on a level with the upper surface of said wheel and shaped at its edge substantially to fit the edge of said wheel.

46 denotes a fixed guide strip or member permanently secured to or formed integral with the table 45 adjacent the exposed edge of the wheel 18, and 47 an adjustable guide strip or member arranged parallel to the guide member 46 and adjustably secured to the table 45 by means of a screw 48 which passes through a slot 49 in said member 47 and enters the table 45, whereby the guide member 47 may be adjusted toward and from the guide member 46 to vary the space between said members in accordance with the diameter of the coins to be counted. The guide members 46 and 47 form between them on the table 45 a coin guideway substantially tangential to the centrifugal wheel 18 and communicating therewith beneath

55 the rejecting wheel 37. The guide member 47 is formed with a pointed end 102 which extends beneath the edge of the wheel 37 and which is recessed to receive said edge.

60 50 denotes a bar carried by the guide member 47 and extending across the coin guideway, thereby preventing the entry of coins into said guideway beyond the periphery of the wheel 37. The bar 50 is spaced above the table 45 a distance sufficient 65 to permit a single coin to pass thereunder

but insufficient to permit the passage of more than one coin at a time.

51 denotes a feeding wheel provided on its periphery with a rubber or other frictional facing which projects through a slot 52 in the table 45 adjacent the guide 47. The feeding wheel 51 is mounted on a shaft 53 journaled in the machine frame and provided with a gear 54 which meshes with a gear 55 on the shaft 21, whereby the feeding wheel 51 is continuously rotated from the shaft 21.

56 denotes a presser wheel journaled on a pin 63 carried between the arms of a yoke 57 pivoted on a stud 58 carried by a bracket 59 secured, as by screws 60, to the rim 44 of the frame 15. The wheel 56 is pressed toward the wheel 51 by means of a spring 61 secured at one end to the stud 58 by a collar 62, surrounding said stud, and bearing at its opposite end upon the pin 63. Downward movement of the wheel 56 under the influence of the spring 61 is preferably limited by means of a stop screw 64 which passes through a lug or ear 65 on the yoke 57 and engages the bracket 59.

66 denotes a counting wheel which is fixed to an upright shaft 67 journaled in the table 45 adjacent the end of the guide member 46, said counting wheel having a suitable number of radial arms, herein shown as five, which extend into the coin guideway and into proximity to the feeding wheel 51 and presser wheel 56. Said counting wheel is positioned with one or another of its arms 100 adjacent said feeding and presser wheels, in the position shown in Figs. 1 and 5, by means of a centering pawl 68 which has an end shaped to fit the space between two of the arms on the wheel 66 and is secured at 105 its opposite end to a pin 69 journaled in the table 45 and provided beneath said table with an arm 70 connected with said table by a spring 71, whereby the free end of said pawl 68 is yieldingly pressed against the 110 counting wheel 66.

72 denotes a skew gear fixed to the upper end of the shaft 67 and meshing with a corresponding skew gear 73 on the shaft of a suitable counting device or register 74 carried by the table 45 and by means of which the number of rotations or fractional rotations of the counting wheel may be registered or indicated.

Beyond the wheels 51 and 56 the table 45 120 is provided with a short chute 75 through which the coins, after passing the counting wheel, may be discharged into a suitable receptacle designed to receive them. As shown in Fig. 1 there is provided a cylindrical 125 receptacle 76 pivoted to the table 45 upon a pin 77 by which said receptacle is suspended in a position to receive the coins discharged from the chute 75 and about which said receptacle may be swung in order to 130

discharge the coins into the hand of the operator when a predetermined number has accumulated.

78 denotes a crank disk secured to the lower end of the shaft 67 and provided with a crank pin 79 and with a stop shoulder 80 (see Figs. 11 and 12).

10 81 denotes a ratchet wheel mounted to rotate on a stud 82 projecting downwardly from the machine frame. Said stud 82 is preferably formed with an enlargement 83 upon which said ratchet wheel is supported.

15 84 denotes a spring surrounding the stud 82 and connected at its opposite ends respectively to the framework and to the ratchet wheel 81, said spring tending normally to rotate the ratchet wheel 81 in a counterclockwise direction.

85 denotes an actuating pawl pivoted on the crank pin 79 and drawn into a position to engage at its end the teeth of the ratchet wheel 81 by means of a spring 86 secured at one end to a pin 87 projecting from said pawl and at the opposite end to the frame-work.

88 denotes a bracket secured to the framework and formed at its lower end with a guard 89 adapted to engage the end of the pawl 85 and hold the same out of engagement with the teeth of the ratchet wheel 81 except through a portion of the travel of said pawl, the arrangement being such that at each rotation of the shaft 67 the pawl 85 will turn the ratchet wheel 81 in a clockwise direction, as shown by the arrow on Fig. 11, the space of one tooth.

90 denotes a holding pawl pivoted to the bracket 88 and held by a spring 91 in a position to engage at its end the teeth of the ratchet wheel and hold said ratchet wheel in the position to which it is advanced by the pawl 85 against the tension of the spring 84. The pawl 90 is provided with a finger piece 92 by means of which said pawl may 45 be moved out of engagement with the ratchet wheel 81, while the pawl 85 is provided with a pin 93 which is engaged by the pawl 90 when the latter is disengaged from the ratchet wheel 81, thereby disen- 50 gaging the pawl 85 also and placing the ratchet wheel 81 under the influence of the spring 84 by which said ratchet wheel is returned to its initial or predetermined position.

55 94 denotes a shouldered stop plate secured to the ratchet wheel 81, as by screws 95. The stop plate 94 is formed with a series of radially extending shoulders arranged at progressively increasing distances from the center of the ratchet wheel.

96 denotes an adjustable stop which, in the construction shown, comprises a slotted plate adjustably secured by means of a clamp screw 97 to a lug 98 projecting from the framework. By adjusting the plate 96

with the end thereof at a greater or less distance from the center of the ratchet wheel 81 said end may be caused to engage any desired shoulder on the stop plate 94, thereby arresting the movement of the ratchet wheel 81 under the influence of the spring 84 at any one of a plurality of points. The shoulders on the plate 94 are preferably designated by numerals indicating numbers of coins which the machine may be adjusted to pass before being brought to rest, as will presently be more fully explained.

99 denotes a stop arm rigidly secured to the ratchet wheel 81 as by means of screws 100. When the ratchet wheel 81 is turned into a certain position the end of the arm 99, as shown in dotted lines in Fig. 11, is brought into a position to be engaged by the stop shoulder 80 on the crank disk 78 when the latter is rotated in the direction of the arrow on Fig. 11 by the shaft 67 and counting wheel 66, thereby locking said shaft and counting wheel against further rotation.

The operation of the machine as thus far described is as follows. The machine is initially set to count coins of any desired denomination by so adjusting the sleeve 39 that the rejecting wheel 37 will be spaced above the centrifugal wheel 18 and table 45 a distance substantially equal to the thickness of the coin chosen. The guide 47 is also so adjusted that the space between its outer edge and the edge of the guide 46, *i.e.* the width of the coin guideway, will be substantially equal to the diameter of such coin. 100

stantially equal to the diameter of such coin. As shown in the drawings the mechanism is adjusted for the purpose of counting one cent pieces, designated by the numeral 101. With the parts so adjusted the coins in question are deposited in the tray 16 and the motor 32 started or the shaft 21 rotated by the crank 22 as desired. A suitable number of coins are then swept from the tray 16 upon the centrifugal wheel 18, which is rotated in the direction of the arrows applied thereto in Figs. 1 and 5. The centrifugal action induced by the rotation of said wheel causes the coins thereon to be thrown to the outer edge thereof where they are retained by the rim 44. As said coins are carried around to the rejecting wheel 37 such of said coins as are in proper position will pass beneath the edge of said wheel. Inasmuch as

heath the edge of said wheel. The result is that the adjustment of said wheel is such that the space between the same and the wheel 18 is equal only to the thickness of one coin it follows that the coins must pass under said wheel one at a time. If two coins are brought to the rejection wheel one superimposed upon the other, as indicated in Fig. 5, said coins will not pass beneath the wheel but, by reason of the direction of rotation of said wheel, will be thrown to the left toward the center of the centrifugal wheel 18 and caused to travel around with said centrif- 120
125
130

ugal wheel again. Any coin of greater thickness than that for which the machine is adjusted, and which may accidentally have found its way into the machine, will 5 be similarly swept aside by the rejecting wheel. Such coins as pass properly beneath the rejecting wheel 37 will, by reason of the centrifugal action and the tangential arrangement of the coin guideway, be carried 10 into said guideway and beneath the bar 50, which, as above explained, co-operates with the rejecting wheel 37 in preventing the passage of more than one coin at a time. Should two coins assume such a position as is indicated 15 in Fig. 1, and which position, by reason of the centrifugal action, might prevent either from passing between the guide members 46 and 47, the end 35 of the spring pusher or clearer 33 will, at the proper time 20 in the rotation of the wheel 18, engage the first of said coins and force it from its position on the pointed end 102 of the guide member 47.

The yielding nature of the pusher 33 prevents any breakage of parts should the coins become so tightly jammed as to be incapable of being pushed aside as above described. The coins having passed the bar 50 pass between the wheels 51 and 56 by which said 30 coins are tightly gripped and positively fed past the counting wheel 66. In passing the latter wheel each coin, by engagement with the adjacent arm on said wheel, causes the same to be turned through one-fifth of a rotation, after which said coin is discharged 35 through the chute 75 into the receptacle 76. The counting wheel occupies a fixed position with respect to the fixed guide member 46 and is normally held by the positioning pawl 40 68 with one of its arms extended into the guideway, and the adjustment of the guide member 47 from the guide member 46 in accordance with the diameter of the coins being counted renders it impossible for a 45 coin to pass between the wheels 51 and 56 without engaging and operating the counting wheel 66 as above described, while the parts hereinbefore referred to render it impossible for the coins to pass through the 50 machine one superimposed upon another, so that as each coin passes through the machine the counting wheel 66 must be turned through one fifth of a rotation. The rotation of said counting wheel is transmitted, through the 55 gears 72 and 73, to the register 74, which is so constructed as directly to indicate the number of coins which have passed the counting wheel. The precise construction of the register 74 forms no part of the present 60 invention and may be of any suitable character familiar to those skilled in the art, the only essential characteristic thereof being that the same be so arranged as to be advanced one number at each fractional rota-

tion of the wheel 66 corresponding to the 65 passage of a coin, in the present instance one-fifth of a rotation.

In order to provide for the automatic stopping of the machine after the delivery therefrom of a predetermined number of 70 coins the following additional adjustments are initially made. The stop 96 is so adjusted as to engage the shoulder on the stop plate 94 corresponding to the number of coins in question. As shown in Fig. 11 the 75 parts are adjusted to count twenty coins, while as shown in Fig. 12 the same parts are adjusted to count fifty coins. The pawls 85 and 90 are then swung outwardly by means of the finger piece 92, thereby releasing the ratchet wheel 81 and permitting the spring 84 to turn the same until the desired shoulder on the plate 94 is brought into engagement with the stop 96. Having been so adjusted the mechanism is started and the 85 coins fed past the counting wheel as above described.

At each complete rotation of the counting wheel 66, corresponding in the construction shown to the passage of five coins, the pawl 90 85 will be given a complete reciprocation, thereby turning the ratchet wheel 81 in a clockwise direction through the space of one tooth. With the parts adjusted as shown in Fig. 11 when the ratchet wheel 81 has 95 been turned through the space of four teeth, corresponding to the passage of twenty coins, the arm 99 will have been turned into the position shown in dotted lines in said figure and will be immediately engaged by 100 the stop shoulder 80, thereby locking the counting wheel 66 against further rotation and positively preventing the passage of any additional coins.

When the machine is automatically operated by a continuously running motor such as that shown at 32 in Fig. 1 it is desirable that this motor be automatically stopped upon the completion of the counting operation in order to prevent unnecessary wear of 105 the parts and particularly of the feeding wheel 51 upon a coin held against movement by the locked counting wheel 66. To this end the following means may be provided, reference being had to Figs. 9, 11 and 110 12: 103 and 104 denote wires or conductors forming a part of the circuit to the electric motor 32. The wire or conductor 103 is connected, as by a binding post of any usual or well-known form, to a fixed contact member 105, while the wire 104 is similarly connected to a pivoted contact member 106 co-operating with the contact member 105, said contact members constituting a switch controlling the circuit to the motor 32. The 115 contact members 105 and 106 are preferably suitably insulated from the machine frame, as by an insulating bushing 115 carried by 120 125

the frame, and to which the member 106 is pivoted by a screw 116, and an insulating plate 117 by which the contact member 105 is carried. 107 denotes a trip finger carried by the arm 99 and preferably insulated therefrom, as by an insulating plate 108. The finger 107 is adapted, when the arm 99 is moved into position to be engaged by the stop shoulder 80, as shown in dotted lines in Fig. 11, to engage the pivoted contact member 106 and separate the same from the contact member 105, thereby breaking the circuit to the motor 32 and stopping the machine.

In order to increase the possible counting capacity of the machine the following mechanism may be provided: 109 denotes an auxiliary ratchet wheel mounted to rotate on the enlargement 83 of the stud 82 below the ratchet wheel 81. Preferably the vertical position of the ratchet wheel 109 is fixed by means of a collar 110 adjustably secured to the reduced lower end 111 of the stud 82 by means of a set screw 112, whereby said auxiliary ratchet wheel 109 may be retained in the inoperative position shown in full lines in Fig. 9 or may be raised into the operative position shown in dotted lines in said figure, in which position said auxiliary ratchet wheel will be engaged by the end of the pawl 85, which is made of a sufficient breadth for this purpose as shown in said figure. The auxiliary ratchet wheel 109 is of slightly greater diameter than the ratchet wheel 81, so that the bases of the teeth of the former lie slightly outside the extremities of the teeth of the latter. When in engagement with the ratchet wheel 109 the pawl 85 is prevented from engaging the teeth of the ratchet wheel 81. One of the teeth of the ratchet wheel 109 is cut to a greater depth than the others so that when in engagement with this tooth the pawl 85 is permitted also to engage the corresponding tooth of the ratchet 81 and operate the latter as well as the ratchet wheel 109. 113 denotes a spring pressed retaining pawl pivoted on an extension of the lug 98 and co-operating with the ratchet wheel 109 to prevent retrograde rotation thereof.

The operation of the mechanism last described is as follows: As shown the auxiliary ratchet wheel 109 is provided with twenty teeth, thereby multiplying by twenty the counting capacity of the machine, inasmuch as, in order to produce a movement of the ratchet wheel 81 through the space of one tooth, the ratchet wheel 109 must be given a complete rotation corresponding to twenty complete rotations of the counting wheel 66. As shown in Fig. 12 the adjustment is such as to provide for the counting of one thousand coins, the stop 96 being set to engage the shoulder marked "50" on the

stop plate 94, which shoulder provides for a movement of ten teeth of the ratchet wheel 81. At each complete rotation of the shaft 67, corresponding to the passage of five coins, the ratchet wheel 109 is advanced one tooth without, however, advancing the ratchet wheel 81. After a complete rotation of the ratchet wheel 109 through the space of twenty teeth, and corresponding to the passage of one hundred coins, the ratchet wheel 81 is advanced one tooth. This operation is continued until the ratchet wheel has been advanced through the space of ten teeth, corresponding to ten times one hundred or one thousand coins, after which the arm 99 is brought into a position to be engaged by the stop shoulder 80 and the mechanism stopped as above described.

Having thus described my invention I claim:

1. In a coin counting machine, in combination, a centrifugal wheel, a shaft operatively connected with said wheel for rotating the same, a manually operated crank for rotating said shaft, a notched collar fast on said shaft, a gear loose on said shaft, a pawl carried by said gear and co-operating with said collar, a motor, and operative connections intermediate said motor and gear.

2. In a coin counting machine, in combination, a centrifugal wheel, a guideway communicating with said wheel, and a pusher carried by said wheel and adapted to engage coins improperly positioned in the mouth of said guideway and move the same away from said guideway.

3. In a coin counting machine, in combination, a centrifugal wheel, a guideway communicating with said wheel, and a spring pusher carried by said wheel and adapted to engage coins improperly positioned in the mouth of said guideway and move the same away from said guideway.

4. In a coin counting machine, in combination, a centrifugal wheel provided with an opening therethrough, a guideway communicating with said wheel, and a spring pusher secured to the under side of said wheel and having an angular end extending through said opening adapted to engage coins improperly positioned in the mouth of said guideway and move the same away from said guideway.

5. In a coin counting machine, in combination, a centrifugal wheel, a pair of guide members forming a guideway communicating with said wheel, one of said guide members having a pointed end extending over said wheel, and a pusher carried by said wheel and adapted to engage coins improperly positioned in the mouth of said guideway and force the same away from the pointed end of said guide member.

6. In a coin counting machine, in combination, a centrifugal wheel and a rejecting wheel overlapping the edge of said centrifugal wheel arranged parallel thereto, and spaced above the same.
7. In a coin counting machine, in combination, a centrifugal wheel, a rejecting wheel overlapping the edge of said centrifugal wheel arranged parallel thereto, and spaced above the same, and means for rotating said wheels in opposite directions.
8. In a coin counting machine, in combination, a centrifugal wheel, a rejecting wheel overlapping the edge of said centrifugal wheel arranged parallel thereto, and spaced above the same, a shaft, and oppositely disposed worm gearing operatively connecting said shaft with said wheels respectively for rotating said wheels in opposite directions.
9. In a coin counting machine, in combination, a centrifugal wheel, a rejecting wheel overlapping the edge of said centrifugal wheel and arranged parallel thereto, and means for adjustably supporting said rejecting wheel in spaced relation to said centrifugal wheel.
10. In a coin counting machine, in combination, a frame having a split portion, a centrifugal wheel journaled in said frame, a rejecting wheel overlapping the edge of said centrifugal wheel, a shaft on which said rejecting wheel is mounted, a sleeve in which said shaft is journaled, said sleeve being adjustably held in the split portion of said frame for supporting said rejecting wheel in variably spaced relation to said centrifugal wheel, and a clamp screw for securing said sleeve in adjusted position.
11. In a coin counting machine, in combination, a centrifugal wheel, a rejecting wheel overlapping the edge of said centrifugal wheel arranged parallel thereto, and spaced above the same, and a coin guideway communicating with said centrifugal wheel beneath said rejecting wheel.
12. In a coin counting machine, in combination, a centrifugal wheel, a rejecting wheel overlapping the edge of said centrifugal wheel arranged parallel thereto, and spaced above the same, a coin guideway communicating with said centrifugal wheel beneath said rejecting wheel, and a pusher carried by said centrifugal wheel and adapted to engage coins improperly positioned in the mouth of said guideway and move the same away from said guideway.
13. In a coin counting machine, in combination, a centrifugal wheel, a rejecting wheel overlapping the edge of said centrifugal wheel and spaced above the same, and a pair of guide members forming a coin guideway communicating with said centrifugal wheel beneath said rejecting wheel, one of said guide members having a pointed end extending beneath said rejecting wheel, said end being recessed on its upper face to receive said rejecting wheel.
14. In a coin counting machine, in combination, a centrifugal wheel, a rejecting wheel overlapping the edge of said centrifugal wheel and spaced above the same, a pair of guide members forming a guideway communicating with said centrifugal wheel beneath said rejecting wheel, one of said guide members having a pointed end extending beneath said rejecting wheel, said end being recessed on its upper face to receive said rejecting wheel, and a pusher carried by said centrifugal wheel and adapted to engage coins improperly positioned in the mouth of said guideway and force the same away from the pointed end of said guide member.
15. A coin counting machine comprising a centrifugal wheel, a rejecting wheel overlapping the edge of said centrifugal wheel arranged parallel thereto, and spaced above the same, a coin guideway communicating with said centrifugal wheel beneath said rejecting wheel and adapted to receive the coins from said centrifugal wheel, and means for counting said coins in their passage through said guideway.
16. A coin counting machine comprising a centrifugal wheel, a rejecting wheel overlapping the edge of said centrifugal wheel and arranged parallel thereto, means for supporting said rejecting wheel in spaced relation to said centrifugal wheel, said supporting means being adjustable to vary the space between said wheels to accommodate coins of different thickness, a coin guideway communicating with said centrifugal wheel beneath said rejecting wheel, said guideway being adjustable in width to accommodate coins of different diameters, and means for counting said coins in their passage through said guideway.
17. A coin counting machine comprising a centrifugal wheel, a rejecting wheel overlapping the edge of said centrifugal wheel arranged parallel thereto, and spaced above the same, a table adjacent the edge of said centrifugal wheel, a pair of guide members on said table forming a coin guideway communicating with said centrifugal wheel beneath said rejecting wheel, one of said members being adjustable on said table with respect to the other of said members to vary the width of said guideway, and counting means supported by said table and extending into said guideway.
18. In a coin counting machine, in combination, a centrifugal wheel, a rejecting wheel overlapping the edge of said centrifugal wheel arranged parallel thereto, and spaced above the same, a coin guideway communicating with said centrifugal wheel beneath said rejecting wheel, a counting

wheel extending into said guideway, means for feeding coins through said guideway past said counting wheel, and a bar extending over said guideway between said rejecting wheel and feeding means to compel the proper passage of the coins from said rejecting wheel to said counting wheel.

23. A coin counting machine comprising a frame, mechanism for feeding and counting coins, a pawl operated by said mechanism, a stud projecting from said frame, a ratchet wheel rotatably mounted on said stud and operated by said pawl, means operated by said ratchet wheel for rendering said feeding and counting mechanism inoperative after a predetermined number of operations, a second ratchet wheel of greater diameter than said first named ratchet wheel but having one tooth cut to the depth of the teeth on said first named ratchet wheel, said last named ratchet wheel being also rotatably mounted on said stud and being movable longitudinally thereof into and out of position for engagement by said pawl, and an adjustable collar on said stud for fixing the position of said last named ratchet wheel.

24. A coin counting machine comprising mechanism for feeding and counting coins, an actuating pawl operated by said mechanism, a ratchet wheel advanced by said pawl, means operated by said ratchet wheel for rendering said feeding and counting mechanism inoperative after a predetermined number of operations, a pawl for holding said ratchet wheel against retrograde movement, and means whereby said pawls may be simultaneously disengaged from said ratchet wheel.

25. A coin counting machine comprising mechanism for feeding and counting coins, an actuating pawl operated by said mechanism and having a projecting pin, a ratchet wheel operated by said pawl, means advanced by said ratchet wheel for rendering said feeding and counting mechanism inoperative after a predetermined number of operations, and a pawl for holding said ratchet wheel against retrograde movement provided with a finger piece for releasing the same, said holding pawl being arranged when released to engage the pin on said actuating pawl and release said actuating pawl.

26. A coin counting machine comprising mechanism for feeding and counting coins, a pawl operated by said mechanism, a ratchet wheel operated by said pawl, a pawl guard for preventing the engagement of said pawl with said ratchet wheel except at predetermined times, and means operated by said ratchet wheel for rendering said feeding and counting mechanism inoperative after a predetermined number of operations.

27. A coin counting machine comprising a counting wheel, means for feeding coins past said counting wheel, locking means associated with said counting wheel, a locking

wheel extending into said guideway, means for feeding coins through said guideway past said counting wheel, and a bar extending over said guideway between said rejecting wheel and feeding means to compel the proper passage of the coins from said rejecting wheel to said counting wheel.

19. In a coin counting machine, in combination, a frame, a table supported by said frame and having an opening, a counting wheel on said table adjacent said opening, a feeding wheel beneath said table and extending through said opening, a shaft, means for rotating said shaft, gears connecting said shaft and feeding wheel, a bracket supported by said frame, a yoke pivoted to said bracket above said table, a presser wheel carried by said yoke and co-operating with said feeding wheel, a spring co-operating with said yoke for pressing said presser-wheel toward said feeding wheel, and a stop carried by said yoke and co-operating with said bracket to limit the movement of said presser wheel toward said feeding wheel.

20. In a coin counting machine, in combination, a centrifugal wheel, a rejecting wheel overlapping the edge of said centrifugal wheel and spaced above the same, means for rotating said wheels in opposite directions, a guideway communicating with said centrifugal wheel beneath said rejecting wheel, and a pusher carried by said centrifugal wheel and adapted to engage and dislodge coins improperly positioned in the mouth of said guideway.

21. A coin counting machine comprising mechanism for feeding and counting coins, a pawl operated by said mechanism, a ratchet wheel operated by said pawl, means operated by said ratchet wheel for rendering said feeding and counting mechanism inoperative after a predetermined number of operations, and a second ratchet wheel of greater diameter than said first named ratchet wheel arranged concentric therewith and also engaged by said pawl, said last named ratchet wheel having a plurality of peripheral teeth one of which is cut to a sufficient depth to permit said pawl to engage said first named ratchet wheel.

22. A coin counting machine comprising mechanism for feeding and counting coins, a pawl operated by said mechanism, a ratchet wheel operated by said pawl, means operated by said ratchet wheel for rendering said feeding and counting mechanism inoperative after a predetermined number of operations, and a second ratchet wheel of greater diameter than said first named ratchet wheel and having a plurality of peripheral teeth one of which is cut to the depth of the teeth on said first named ratchet wheel, said last named ratchet wheel being co-axially arranged with respect to

member coöperating with said locking means for locking said counting wheel against operation, and means operated by said counting wheel for progressively moving said locking member toward locking position.

28. A coin counting machine comprising a counting wheel, means for feeding coins past said counting wheel, a shaft on which said counting wheel is mounted, a crank pin carried by said counting wheel shaft, means for locking said counting wheel against operation, and means operated by said crank pin for progressively moving said locking means toward locking position.

29. A coin counting machine comprising a counting wheel, means for feeding coins past said counting wheel, a shaft on which said counting wheel is mounted provided with a stop shoulder, a stop arm for engaging said shoulder and locking said shaft, and means operated by said shaft for progressively moving said stop arm toward locking position.

30. A coin counting machine comprising a counting wheel, means for feeding coins past said counting wheel, a shaft on which said counting wheel is mounted provided with a stop shoulder, a stop arm for engaging said shoulder and locking said shaft, means operated by said shaft for progressively moving said locking arm toward locking position, an electric motor for actuating said feeding means, a switch for controlling the circuit to said motor, and means on said stop arm for opening said switch when said stop arm is in locking position.

31. A coin counting machine comprising a counting wheel, means for feeding coins past said counting wheel, a shaft on which said counting wheel is mounted provided with a stop shoulder, a stop arm for engaging said shoulder and locking said shaft, a crank pin carried by said shaft, and means operated by said crank pin for progressively moving said stop arm toward locking position.

32. A coin counting machine comprising mechanism for feeding and counting coins, a member progressively moved in one direction by said mechanism from a predetermined starting point, means operated by said member for rendering said mechanism inoperative when said member has been moved to a predetermined point, and means for limiting the movement of said member in the opposite direction to determine said starting point.

33. A coin counting machine comprising mechanism for feeding and counting coins, a progressively movable member, means operated by said member when moved to a predetermined point for rendering said mechanism inoperative, means operated by said mechanism for progressively moving

said member, said last named means being movable to release said member, and means for automatically moving said member, when released, into a predetermined starting position.

34. A coin counting machine comprising mechanism for feeding and counting coins, a progressively movable member, means operated by said member when moved to a predetermined point for rendering said mechanism inoperative, means operated by said mechanism for progressively moving said member in a forward direction, said last named means being movable to release said member, means for moving said member in a retrograde direction when released, and adjustable means for limiting the retrograde movement of said member.

35. A coin counting machine comprising mechanism for feeding and counting coins, a member progressively moved in one direction by said mechanism, means operated by said member for rendering said mechanism inoperative when moved to a predetermined point, a stop plate secured to said member and provided with a series of shoulders, and a stop coöperating with said stop plate for limiting the movement of said member in the opposite direction, said stop being adjustable to cause the same to engage any of the shoulders on said stop plate.

36. A coin counting machine comprising a frame, mechanism for feeding and counting coins, a member progressively moved in one direction by said mechanism, means operated by said member for rendering said mechanism inoperative when moved to a predetermined point, a stop plate secured to said member and provided with a series of shoulders, a slotted plate coöperating with said stop plate for limiting the movement of said member in the opposite direction, and a screw passing through the slot in said plate for adjustably clamping the same to said frame in position to engage any predetermined shoulder on said stop plate.

37. A coin counting machine comprising mechanism for feeding and counting coins, a member progressively rotated in one direction by said mechanism, means operated by said member for rendering said mechanism inoperative when turned to a predetermined point, a spring for rotating said member in the opposite direction, a stop plate secured to said member and provided with a series of shoulders, and a stop coöperating with said stop plate for limiting the movement of said member under the influence of said spring, said stop being adjustable to cause the same to engage any of the shoulders on said stop plate.

38. A coin counting machine comprising mechanism for feeding and counting coins, an actuating pawl operated by said mechanism, a ratchet wheel progressively rotated

in one direction by said pawl, means operated by said ratchet wheel when turned to a predetermined point for rendering said feeding and counting mechanism inoperative, a holding pawl for said ratchet wheel, means whereby said pawls may be simultaneously disengaged from said ratchet wheel, a spring for rotating said ratchet wheel in the opposite direction when re-

leased by said pawls, and means for limiting 10 the movement of said ratchet wheel under the influence of said spring.

In testimony whereof I affix my signature in presence of two witnesses.

JOHN F. WEBENDORFER.
